CLAIM

We claim the ornamental design for a suspension system for a helmet, as shown and described.

DESCRIPTION

FIG. 1 is a bottom plan view of a suspension system for a helmet of the present disclosure;

FIG. 2 is a front perspective view of the suspension system for a helmet of FIG. 1;

FIG. 3 is a rear perspective view of the suspension system for a helmet of FIG. 1;

FIG. 4 is a first side perspective view of the suspension system for a helmet of FIG. 1;

FIG. 5 is a second side perspective view of the suspension system for a helmet of FIG. 1;

FIG. 6 is a bottom plan view of the suspension system for a helmet of FIG. 1;

FIG. 7 is a front perspective view of the suspension system for a helmet of FIG. 1;

FIG. 8 is a first side perspective view of a suspension system for a helmet of FIG. 1;

FIG. 9 is a second side perspective view of the suspension system for a helmet of FIG. 1; and,

FIG. 10 is a rear perspective view of the suspension system for a helmet of FIG. 1.

The broken lines of the article depict portions of the article that form no part of the claimed design. The broken line helmet shown in FIGS. 1-5 depicts environment and forms no part of the claimed design. The dash-dot broken lines represent the bounds of the claimed design and form no part of the claimed design.

Dash-dot lines adjacent un-shaded areas represent bounds of the claimed design and form no part of the claimed design themselves.
